CLAIM

The ornamental design for a vehicle cab cover with logo, as
shown and described.

DESCRIPTION

FIG. 1 is a perspective view of the vehicle cab cover with
logo showing my new design;

FIG. 2 is a bottom plan view thereof;

FIG. 3 is a top plan view thereof;

FIG. 4 is a left elevation view thereof;

FIG. 5 is a right elevation view thereof;

FIG. 6 is a front elevation view thereof; and,

FIG. 7 is a rear elevation view thereof.

Broken lines are included for depicting environmental sub-
ject matter and form no part of the claimed design.
